UNITED STATES PATENT OFFICE.

JOSEPH STEGER, OF NEW YORK, N. Y., ASSIGNOR TO CHARLES W. BAKER,
OF SAME PLACE.

IMPROVEMENT IN DEVICES FOR STOPPING AND STARTING RAILROAD-CARS.

Specification forming part of Letters Patent No. 39,999, dated September 15, 1863.

To all whom it may concern:

Be it known that I, JOSEPH STEGER, of the city, county, and State of New York, have invented a new and Improved Device for Stopping and Starting Railroad-Cars; and I do hereby declare that the following is a full, clear, and exact description of the same, reference being had to the accompanying drawings, forming a part of this specification, in which—

Figure 1 represents a plan or top view of my invention. Fig. 2 is a longitudinal vertical section of the same, the line $x\ x$, Fig. 1, indicating the plane of section. Fig. 3 is a transverse vertical section of the same, taken in the plane indicated by the line $y\ y$, Fig. 1. Fig. 4 is a detached sectional view of the internal gear, the line $z\ z$, Fig. 3, indicating the plane of section.

Similar letters of reference in the several views indicate corresponding parts.

The object of this invention is to accumulate or save the momentum of a car as the same is stopped, and to apply the momentum thus saved to start or to assist in starting the car.

The nature of my invention and the mechanism which I employ to effect my purpose will be readily understood from the following description.

A represents the body of a railroad-car, which is supported by four wheels, B B', attached to the axles C C', in the ordinary manner.

D is a drum, which is rigidly secured to the hollow shaft E of the pinion F, and which connects, by means of a cord, a, with a spring, G, that is inclosed in a tubular case, H. This case is secured to the end of the car or otherwise attached to the frame or platform of the same, and the cord a is secured to the spring G in such a manner that when the drum is rotated the cord winds on the same and the spring is gathered up or compressed. The hollow shaft E, which bears the drum D, is placed loosely on the axle C, and it is made to rotate with said axle by a friction-clutch, I, which slides on the said axle, being compelled to revolve with the same by a suitable key or feather. This friction-clutch is applied to the drum by means of a hand-lever, J, that is se-

cured to the end of a rock shaft, b, which bears two tappets, c. By throwing said hand-lever in the direction of the arrow marked near it in Figs. 1 and 3, the tappets press against the outer surface of the clutch and force the same up against the drum, causing the same to rotate with the axle C and to wind up the spring G. The pinion F on the end of the tubular shaft E gears into a similar pinion, K, which rotates on a stud, l, secured in a disk, e, that is fastened to the body of the car by means of a bracket, f. The pinion K meshes into an internal gear, g, on the inner surface of a drum, L, which rotates freely on the axle C.

M is a friction-clutch which slides on the axle C, being compelled to rotate with the same by means of a key, h. This clutch is forced up against the drum L by tappets i, secured to a rock-shaft, j, which is operated by a treadle, k. This treadle connects with the rock-shaft by suitable levers or arms in such a manner that by throwing the treadle in the direction of the arrow marked near it in Figs. 1 and 3 the friction-clutch M is caused to bear against the drum L and to partake of the motion which may be imparted to said drum.

The operation is as follows: If the car moves in the direction of the arrow marked near it in Fig. 1, and it is desired to stop the same and to accumulate its momentum, the hand-lever J is thrown in the direction of the arrow marked near it in Figs. 1 and 3, and the clutch I is pressed up against the drum D. The spring G is forced up by the action of the cord a and the car-stops. When it is desired to start the car, the treadle k is depressed. By the action of this treadle the friction-clutch M is forced up against the drum L, and at the same time the hand-lever J is forced back, so that the clutch I releases the drum D, and the latter is forced to follow the action of the spring G. By the action of the internal gear, F K g, the motion of the drum D is transmitted to the drum L, and thence by the action of the clutch M to the axle C. The internal gear is so arranged that the motion of the axle will be in a forward direction, and the operation of starting the car is considerably facilitated.

What I claim as new, and desire to secure by Letters Patent, is—
